(57) **CLAIM**

The ornamental design for a secondary package having a surface design, as shown and described.

DESCRIPTION

The present application file contains at least one drawing executed in color. Copies of this patent or patent application publication with color drawing(s) will be provided by the Office upon request and payment of the necessary fee.

FIG. 1 is a perspective view of a secondary package having a surface design embodying our new design;

FIG. 2 is a front view thereof;

FIG. 3 is a back view thereof;

FIG. 4 is left/right side view thereof;

FIG. 5 is a top side view thereof;

FIG. 6 is a bottom view thereof;

FIG. 7 is a perspective view of a second embodiment of a secondary package having a surface design embodying our new design;

FIG. 8 is a front view thereof;

FIG. 9 is a back view thereof;

FIG. 10 is a left/right side view thereof;

FIG. 11 is a top view thereof;

FIG. 12 is a bottom view thereof;

FIG. 13 is a perspective view of a third embodiment of a secondary package having a surface design embodying our new design;

FIG. 14 is a front view thereof;

FIG. 15 is a back view thereof;

FIG. 16 is a left/right side view thereof;

FIG. 17 is a top view thereof;

FIG. 18 is a bottom view thereof;

FIG. 19 is a perspective view of a fourth embodiment of a secondary package having a surface design embodying our new design;

FIG. 20 is a front view thereof;

FIG. 21 is a back view thereof;

FIG. 22 is a left/right side view thereof;

FIG. 23 is a top view thereof;

FIG. 24 is a bottom view thereof;

FIG. 25 is a perspective view of a fifth embodiment of a secondary package having a surface design embodying our new design;

FIG. 26 is a front view thereof;

FIG. 27 is a back side view thereof;

FIG. 28 is a left/right side view thereof;

FIG. 29 is a top view thereof;

FIG. 30 is a bottom view thereof;
FIG. 31 is a perspective view of a sixth embodiment of a secondary package having a surface design embodying our new design;
FIG. 32 is a front view thereof;
FIG. 33 is a back view thereof;
FIG. 34 is a left/right side view thereof;

FIG. 35 is a top view thereof; and,
FIG. 36 is a bottom view thereof.
Broken lines are included herein for illustrative purposes only and form no part of the claimed design.
